STRAP-END ATTACHING CLASP

Filed Jan. 12, 1945

UNITED STATES PATENT OFFICE

2,455,465

STRAP-END ATTACHING CLASP

Abraham Blumstein, Forest Hills, N. Y.

Application January 12, 1945, Serial No. 572,537

5 Claims. (Cl. 24—265)

1

This invention relates to clasps or fasteners of the type employed for securing the ends of cords or straps used in wrist watch bands, bracelets or similar articles.

The invention is directed to the provision of a novel clasp of the aforementioned character having improved characteristics as compared with analogous devices of the prior art, particularly with regard to means for attaching the ends of the cords to the clasp and the security of such attachment.

It is also an object of the invention to provide a clasp which is simple in construction and pleasing in appearance, easily assembled, sturdy and durable in use and such as to permit of the ready insertion and clamping of the cord ends therein.

Another and more specific object of the invention is to eliminate the use of a clamping member received within the hollow or channel member into which the end of the cords are inserted and maintained in clamping position therein by friction, such as is generally adopted in the prior art devices, and to insure the clamping of the cord ends by means of a member arranged outwardly of the channel member and conformed for interlocking engagement therewith.

The invention also contemplates the provision of a gripper member for the ends of the cords, associated with a clamping member of the character aforesaid in such a manner as to be pressed into gripping engagement with the ends of the cords and to be concurrently locked in such a position by the clamping member when this latter is locked to the channel member as aforementioned.

These and other objects will become apparent in the following description of the invention illustrated in the drawings.

In the drawings:

Fig. 1 is a top plan view of a wrist watch band showing terminal clasps according to the invention applied to the ends of the band cords.

Fig. 2 is an enlarged top view of one of the clasps.

Fig. 3 is a bottom plan view of the clasp of Fig. 2.

Fig. 4 is a vertical longitudinal section through the clasps, on line 4—4 of Fig. 2, showing the relative position of the ends of the cords and of the constituent elements of the clasps when this latter is closed, the gripper and clamping members of the clasps being also shown in broken lines in an open position thereof to illustrate the operation of the clasps.

2

Fig. 5 is an end view of the clasp showing means coacting to grip the ends of the cords, provided at one end of the structure.

Fig. 6 is an end view of the clasp illustrating the opposite end thereof.

Fig. 7 is a perspective view of the channel member forming part of the clasp.

Fig. 8 is a perspective view of the gripper member.

Fig. 9 is a perspective view of the clamping member.

Referring now in detail to the drawings, numeral 10 generally indicates a clasp according to the invention. By way of illustration, two of said clasps are shown in Fig. 1 applied to the ends of oppositely extending pairs of cords 11 forming part of a wrist watch band, the clasps being interconnected by a suitable fastener 12 to complete the band.

The clasp 10 consists of the three members shown isolated in Figs. 7 to 9, namely a body or channel member 14, a gripper member 15 and a locking or clamping member 16, the construction and manner of assembly whereof will now be described.

The body 14, which is of elongated channel-like conformation and is open at the bottom thereof, comprises parallel side walls 18 and a flat top wall 19; this latter is bent at one of its ends to provide a downwardly extending terminal edge cut to define therein a plurality of teeth or serrations 20. The wall 19 terminates, at its end remote from the serrations 20, inwardly of the ends of the side walls 18 to define a recess 21 for the fastener 12, which may be of any suitable construction and engages the transverse element 22 interconnecting said ends of the side walls 18 and preferably formed integral therewith.

A further smaller opening or slot 24 is provided in the top wall 19, and the side walls 18 are undercut at their ends opposite the transverse element 22 to form recessed portions 25 underneath the serrations 20, for the purpose that will become later apparent.

The gripper member 15 has one end pivotally mounted within the side walls of the channel member 14 adjacent the lower edge thereof by means of projections 26 received within openings 27 of said walls, so as to be movable to a position to form a bottom closure for the channel member. Adjacent its free end, the gripper member is provided with lugs 28 adapted to abut against the lower edge of the side walls 18 at the aforementioned recessed portions 25 thereof, and has projections 30 extending outwardly of the side

walls. The free end of the gripper member is bent to define an upwardly extending terminal edge provided with serrations 32; when the clasp is closed, said serrations extend toward the serrations 20 of the channel member, as illustrated in Figs. 4 and 5, and cooperate with these latter to grip and hold the ends of the cords 11 within the clasp.

The clamping member 16 comprises a pair of spaced parallel legs 34, and a connecting end portion 36 solid or rigid therewith. The legs 34 embody, near the ends thereof, openings 35 adapted to receive the projections 30 of the gripper member to pivotally connect the clamping member thereto. The end portion 36 of the clamping member extends at an angle to said legs 34, as best seen in Fig. 4, and is provided with a substantially resilient hook-shaped projection 37, which is adapted to be inserted into the aforementioned opening 24 of the top wall 19 of the channel member 14 when the clamping member is moved to the position illustrated in Fig. 4, to lock the clasp in closed position. As will be apparent, the end portion 36 and the legs 34 of the clamping member define an opening 38 through which the cords may be passed for insertion into the channel member. The outer surface of the portion 36 may be decorated to enhance the ornamental appearance of the clasp.

The manner in which the clasp is applied to the ends of the cords and these latter clamped therein, will be evident from the foregoing description and from the showing of Fig. 4.

Assuming that the clasp has been opened, so that the pivoted gripper and clamping members 15 and 16 have been allowed to move to an open position such as illustrated in broken lines in Fig. 4, the ends of the cords 11 may be passed through the opening 38 defined in the clamping member, as aforementioned, to overlie the inner face of the gripper member and the serrations 32 thereof; by then swinging the gripper member toward the channel member to close the bottom of this latter, the cords are caused to enter the channel member and to be engaged by the oppositely projecting serrations 32 and 20. The clamping member is then rotated about the pivots 30 to superimpose the portion 36 thereof upon the top wall 19 of the channel member and force the projection 37 to snap into the slot 24 to engage the edge of this latter, thereby locking the clasp with its several members in the closed position shown in full lines in Fig. 4. The movement of the clamping member to locking position will concurrently draw the free end of the gripper member toward the opposed end of the top wall 19, as in a camming action, so that the serrations 32 will press upon the ends of the cords and will be locked in such pressure exerting position, thereby securely clamping the cord ends within the clasp. Manifestly, the structure described affords an absolute security of the attachment of the cords.

It is to be understood that while I have described and illustrated a preferred embodiment of the invention, certain changes and modifications may be made therein without departing from the spirit of the invention or exceeding the scope of the claims.

I claim:

1. A clasp for the ends of cords and the like, comprising a channel member open at the bottom and at one end thereof to receive the ends of the cords, a gripper member having one end pivoted to the side walls of said channel member at a

point remote from the open end thereof, said gripper member having an open and a clamping position, said gripper member extending substantially to said open end along the bottom of the channel member to close said bottom when in said clamping position, means at the free end of the gripper member for gripping the cords without penetration therein in cooperation with means provided in said open end of said channel member when said gripper member is in said clamping position thereof, a clamping member having an inoperative and an operative position, said clamping member embodying an end portion juxtaposed to the top wall of the channel member when said clamping member is in said operative position and portions projecting from said end portion pivotally connected to the free end of the gripper member, said portions extending externally of the channel member and maintaining the gripper member in said clamping position thereof when the clamping member is in said operative position thereof, and interengaging means on the top wall of the channel member and the end portion of the clamping member for releasably locking this latter to the top wall of the channel member.

2. A clasp for the ends of cords and the like, comprising a channel member open at the bottom and at one end thereof to receive the ends of the cords, a gripper member having one end pivoted to the side walls of said channel member at a point remote from the open end thereof, said gripper member having an open and a clamping position, said gripper member extending to said open end along the bottom of the channel member to close said bottom when in said clamping position, serrations oppositely projecting from the top wall of the channel member and from the gripper member for gripping the cords without penetration therein when said gripper member is in said clamping position thereof, a clamping member having an operative and an inoperative position, said clamping member embodying an end portion juxtaposed to the outer face of the top wall of the channel member when said clamping member is in said operative position and side portions projecting from said end portion and pivotally connected to the sides of the gripper member at the free end thereof, said side portions extending externally of the channel member and maintaining the gripper member in said clamping position thereof when the clamping member is in said operative position thereof, and interengaging means on the top wall of the channel member and the end portion of the clamping member for releasably locking this latter to the top wall of the channel member.

3. A clasp for the ends of cords and the like, comprising a channel member open at the bottom and at one end thereof to receive the ends of the cords, said channel member embodying a top wall having a slot therein, a gripper member having one end pivoted to the side walls of said channel member at a point remote from the open end thereof, said gripper member having an open and a clamping position, said gripper member extending substantially to said open end along the bottom of the channel member to close said bottom when in said clamping position, means at the free end of the gripper member for gripping the cords without penetration therein in cooperation with means provided in said open end of said channel member when said gripper member is in said clamping position thereof, a clamping member having an inoperative and an opera-

tive position, said clamping member embodying an end portion juxtaposed to the top wall of the channel member when said clamping member is in said operative position and portions projecting from said end portion pivotally connected to the free end of the gripper member said portions extending externally of the channel member and maintaining the gripper member in said clamping position thereof when the clamping member is in said operative position thereof, and means projecting from the end portion of the clamping member insertable into said slot in the top wall of the channel member to releasably lock the clamping member to the top wall of the channel member.

4. A clasp for the ends of cords and the like, comprising a channel member open at the bottom and at one end thereof to receive the ends of the cords, said channel member embodying a top wall having a slot therein, a gripper member having one end pivoted to the side walls of said channel member at a point remote from the open end thereof, said gripper member having an open and a clamping position, said gripper member extending to said open end along the bottom of the channel member to close said bottom when in said clamping position, serrations oppositely projecting from the top wall of the channel member and from the gripper member for gripping the cords without penetration therein when the gripper member is in said clamping position thereof, a clamping member having an operative and an inoperative position, said clamping member embodying an end portion juxtaposed to the outer face of the top wall of the channel member when said clamping member is in said operative position and side portions projecting from said end portion and pivotally connected to the sides of the gripper member at the free end thereof, said side portions extending externally of the channel member and maintaining the gripper member in said clamping position thereof when the clamping member is in said operative position thereof, and a resilient element projecting from the end portion of the clamping member insertable into said slot in the top wall of the channel member to releasably lock the clamping member to the top wall of the channel member.

5. A clasp for the ends of cords and the like, comprising a channel member open at the bottom

5

and at one end thereof to receive the ends of the cords, a gripper member having one end pivoted to the side walls of said channel member at a point remote from the open end thereof, said gripper member having an open and a clamping position, said gripper member extends substantially to said open end along the bottom of the channel member to close said bottom when in said clamping position, serrations projecting upwardly at the free end of the gripper member for gripping the cords without penetrating therein in cooperation with downwardly projecting serrations provided in said open end of said channel member when said gripper member is in said clamping position thereof, a clamping member having an operative and an inoperative position, said clamping member embodying an end portion juxtaposed to the top wall of the channel member when said clamping member is in said operative position and integral spaced legs projecting from said end portion at an angle therewith and pivotally connected to the sides of the gripper member adjacent the free end thereof, said legs extending in juxtaposition to the side walls of the channel member externally thereof and maintaining the gripper member in said clamping position thereof when the clamping member is in said operative position thereof, and means for releasably locking the end portion of the clamping member to the top wall of the channel member.
